UNITED STATES PATENT OFFICE.

OLAF W. JOHNSON, OF SEATTLE, WASHINGTON, ASSIGNOR, BY DIRECT AND MESNE ASSIGNMENTS, TO BAKERIES SERVICE CORPORATION, OF CHICAGO, ILLINOIS, A CORPORATION.

CARD OR PAMPHLET HOLDING AND FEEDING DEVICE.

Application filed February 28, 1924. Serial No. 695,751.

To all whom it may concern:

Be it known that I, OLAF W. JOHNSON, a citizen of the United States, and a resident of Seattle, King County, Washington, have 5 invented certain new and useful Improvements in Card or Pamphlet Holding and Feeding Devices, of which the following is a specification.

This invention relates to card or pamphlet holding and feeding mechanism; more particularly it relates to a device of that character designed for use in connection with machines whereby loaves of bread are wrapped; it being the object of the invention to provide means operable by and in conjunction with the bread wrapping mechanism whereby novelties and printed matter such as cards and pamphlets, may be delivered singly onto each loaf of bread just 20 before the wrappers are applied.

Another object of the invention resides in the provision of a card or pamphlet container of novel construction wherein the cards or pamphlets may be stacked upon a 25 spring pressed feed member and from which they are delivered, one at a time, by contact with the top card or pamphlet of friction feed rollers operated by a driving connection with the bread wrapping machine.

Other objects of the invention reside in the various details of construction and combination of parts embodied in the invention, and in their mode of operation.

In accomplishing these and other objects of the invention, I have provided the improved details of construction, the preferred forms of which are illustrated in the accompanying drawings, wherein—

Figure 1 is a perspective view of a card or pamphlet holding device and feed mechanism embodied by the present invention.

Figure 2 is a perspective view, showing the opposite side of the card or pamphlet holder from that shown in Figure 1; the door of the housing being open.

Figure 3 is a central vertical section of the device.

Figure 4 is a perspective view of the flexible retainer.

50

Figure 5 is a top view of the device.

Referring more in detail to the several views of the drawings—

1 designates a housing or container wherein the card or pamphlet may be 55 stacked. Preferably the housing would be of sheet metal construction and provided at one side with a door 2 through which the cards or pamphlets may be placed within the same, and having an opening 3 at the top through which the top card or pamphlet of the pack will be exposed to the feed mechanism, presently described.

The pack of cards or pamphlets, designated at 4, is supported within the housing upon a horizontal plate 5 which is fixed upon the upper ends of rods 6 which extend through openings 7 in the bottom wall 8 of the housing, and, at their lower ends, are attached to a plate 9. To the plate 9 are attached the lower ends of a plurality of tensioned springs 10 which act to lift the rods and plate to maintain the top of the pack 4, adjacent the top of the housing, in proper relation to the feed mechanism. 60 These springs are attached, at their upper ends, to a pair of horizontal, parallel bars 11 and 12 upon which the housing 1 is mounted for slight vertical movement.

The present device, when used with a 65 bread wrapping machine, is disposed adjacent the upward line of travel of the loaves.

As is shown in Figure 3, each loaf of bread 13 passes upwardly along the housing 1 and strips of wrapping paper, one of which is shown at 14, are delivered into the path of the loaf as it passes above the housing. Mechanism, not shown, then causes the paper to be wrapped about the loaf. The present device delivers cards or pamphlets, 70 one at a time, onto the loaves just before they come in contact with their wrapper, and the latter then serves to hold the cards or pamphlets and to draw them from the delivery opening of housing.

75

The means provided for feeding the cards

95

or pamphlets to the loaves comprises a pair of corrugated, rubber feed rollers 16 on a rotatably fixed shaft 17 that extends horizontally across the top opening of the container and which is supported independent of the housing 1. These rollers are adapted to come into rubbing contact with the top card or pamphlet of the pack and to thereby cause it to be advanced to the position 10 as shown in dotted lines at 20 in Figure 3 where it will be caught-up between the advancing loaf and its wrapper. As the top card or pamphlet is withdrawn from the pack, the next lower one of the pack is held 15 temporarily by a rubber pad 21 at the end of a spring plate 22 that is supported from the top wall 23 of the housing. This pad yieldingly resists the withdrawal of the card or pamphlet but is not sufficient to 20 overcome the pull of the feed rollers 16.

In order that the feeding of cards or pamphlets will not be overlapping or continuous, I have cut out segments of the feed rollers, as shown at 25. This provides for 25 proper synchronized delivery of the cards or pamphlets in accordance with movement of the loaves of bread.

To more accurately guide the cards or pamphlets into position to be received by the 30 bread, I provide the housing, at the edge of the delivery opening 3, with an inclined lip 26 across which, in spaced relation, is a wire 27 which will prevent the cards or pamphlets, after being released by the feed rollers 16, from falling from position.

To prevent the feeding of more than one card or pamphlet at a time, I have attached a plate 30 to the inner wall of the housing, and this has its upper edge at such level 40 that it will retain the second card or pamphlet from the top of the pack, but will permit the top one to be advanced. Ordinarily, such a plate is not necessary, but sometimes becomes so if the cards or pamphlets are of 45 such a nature that they tend to stick together.

Should it be desired to discontinue feeding of the cards or pamphlets at any time, the housing 1 may be lowered so as to cause the feed rollers 16 to be disengaged from the 50 pack. This lowering is effected by means of a lever 35 that is pivotally fixed, as at 36, to a cross bar 37 extended between and fixed to the bars 11 and 12. At its inner end this lever is connected with a looped strap 38 55 attached centrally to the bottom wall of the housing and at its outer end has a handle 39 whereby it may be raised or lowered and seated within notches 40 of a plate 41 that would be fixed to a rigid member of the machine. When the outer end of this lever is 60 raised it causes the housing containing the pack to be lowered and consequently the disengagement of the feed rollers from the pack. When the lever is released from the 65 plate 41, the housing will be lifted into feed-

ing position where it is yieldingly retained by means of a spring 42 that is coiled about a pin 43 extended through the looped strap 38 with its ends bearing downwardly against the supporting bars 11 and 12. The housing is retained functionally in position and its upward movement limited by means of straps 45 looped about the bars 11 and 12 and secured to the housing in such manner as to permit only vertical movement thereof. 70

While this construction is designed for a certain type of machine, it is readily apparent that by slight variations in details of construction, it could be adapted to other types of machines without departing from the spirit of the invention and for this reason I do not wish to be confined only to details herein shown.

Having thus described my invention, what I claim as new therein, and desire to secure by Letters-Patent of the United States, is:

1. The combination with a wrapping machine of a card or pamphlet holding and feeding device comprising a housing having a delivery opening at the top, supporting means for the housing whereby it is permitted a slight vertical travel, yieldable means within the housing whereon a card or pamphlet pack may be supported and maintained adjacent the delivery opening of the housing; rotatably driven feed rollers operable through the opening for engaging the cards or pamphlets to feed them, one at a time, from the housing, yieldable means normally retaining the housing at its upper limit of travel and means for moving it downwardly to disengage the card or pamphlet pack from the feed rollers. 90

2. In a device of the class described, a housing for containing a card or pamphlet pack having a top delivery opening through which cards or pamphlets may be discharged from the housing, friction feed rollers disposed to engage the top of the pack to feed the cards or pamphlets singly from the pack; said housing having a laterally turned lip at the edge of said opening over which the cards or pamphlets are discharged, and a cross member in spaced relation above the lip which co-operates with the lip to support the cards or pamphlets after being released by the feed rollers. 100

3. A card or pamphlet holding and feeding mechanism, comprising a housing for containing a card or pamphlet pack, and having a top opening through which said cards or pamphlets may be discharged, supporting bars for the housing, a horizontal plate within the housing on which the card or pamphlet pack may be mounted, rods fixed to the said plate and extended downwardly from the housing, a plate fixed to the lower ends of said rods, springs attached to the latter plate and to the housing supports whereby the pack is yieldingly re- 110

- tained adjacent the top opening, a feed shaft extended across the said opening, friction feed rollers on said shaft for delivering the cards or pamphlets singly from the housing,
5 a spring interposed between the base of the housing and said supporting bars for retaining it in operative relation to the feed roll-
- ers, and means for depressing the spring and for adjusting the housing downwardly from the feed rollers to discontinue the discharge 10 of cards or pamphlets.

Signed at Seattle, King County, Washington, this 19th day of January, 1924.

OLAF W. JOHNSON.
